UNITED STATES PATENT OFFICE.

CHARLES JOHANSON, OF DOVER, NEW JERSEY.

SHEET-METAL-FORMING MACHINE.

Application filed August 14, 1925. Serial No. 50,298.

This invention relates to sheet metal forming machines, and particularly to a machine for turning edges on caps and bonnets of sheet iron.

5 An object of this invention is to provide a machine adapted to turn the edges on caps and bonnets of sheet iron and set down the same for double seaming and to accomplish the double function in a single machine.

10 A further object of this invention is to provide attachments for an ordinary bed which are adapted to perform the aforesaid functions in a simple and easy manner.

15 With the foregoing and other objects in view, I have invented the device shown in the accompanying drawings, in which:

Figure 1 is a side elevation of my improved machine.

Figure 2 is a top plan view thereof.

20 Figure 3 is an end elevation thereof.

Figure 4 is a detail of a portion of the drive shaft.

Figure 5 is a detail of the end of the drive shaft.

25 Figure 6 is a section at 6—6 of Figure 5.

Figure 7 is an end elevation of a shaping roller.

Figure 8 is a side elevation partly in section of the roller shown in Figure 7.

30 Figure 9 is a side elevation of the shaft journal support member detached.

Figure 10 is a like view to Figure 9, at right angles thereto.

Figure 11 is a section at 11—11 of Figure 9.

Like reference characters indicate like parts throughout the several views and in the specification, in which there is provided a table 2, which may be of the usual form of

40 table, carrying a head 3, which journals a pair of shafts 4 and 5 passing through the head 3 and driven by co-meshing gears 6 and 7, which gears in return, through a train of gears 8, drive a gear 9, which gear 9 is

45 affixed to a shaft 10, which shaft 10 passes beneath the table 2 and is journaled in the ends of the table, the table 2 being supported by legs 11.

Slidably mounted upon the table 2 is a 50 turret 12 carried by a plate 13 and clamped in predetermined positions upon the table 2 by a clamp lever 14. Slidably mounted upon the shaft 10 and carried by the plate 13 is a bracket journal 15, carrying therewith a bevel gear 16, the shaft 10 being provided

with a longitudinal key extending substantially the entire length of the shaft 10, and the bevel gear 16 being slidable upon the key and adapted to be turned by the key upon the shaft 10. Carried depending from the turret 12 is a vertical shaft 17 journaled in a vertical conical bearing member 18 and affixed to the turret 12 so as to rotate the turret therewith, and carrying at its lower end a bevel gear 19, which bevel gear 19 meshes with the bevel gear 16 and moves in mesh with the gear 16 upon the sliding of the plate 13 upon the bed or table 2. The turret 12 is adapted to carry the disk or cap or other work to be performed, which is held flat upon the table by a roller 20, which roller 20 is adjustable upon a bar 21 supported by a bracket 22, the adjustment being set by a wing nut 23. At the side of the turret 12 is a further guide or work support roller 24 adapted to engage the flanged edges of the work as carried upon the turret 12, the roller 24 being supported by a shaft 25, the shaft 25 being carried by a bracket 26, the bracket 26 slidable upon a bar 27, there being two of the bars 27, which bars 27 are supported by a transverse plate 28 mounted on the bed 2, the plate 28 being adjustable longitudinally of the bed 2 and the bars 27 being provided with an angular adjustment 29 for suitably spacing the bars apart in a desired or predetermined relation. A forming roller 30 is carried by a shaft 31, which shaft 31 is journaled in a vertically movable bearing box 32, and is provided with a universal joint 33, which shaft is shown more in detail in Figure 4, the universal joint 33 having extending therefrom a stub shaft element 34 over which is a sleeve 35 longitudinally slideable upon the stub shaft 34 and anchored thereto to rotate therewith by a pin 36 slideable in a slot 37, whereby the sleeve 35 may have a longitudinal movement relative to the stub shaft 34, but will rotate with the shaft 34, thus permitting of a lengthening or shortening of the drive shaft 31. Carried at the end of the drive shaft 31 is a wheel chuck or support 38 provided at its terminal with a stub shaft 39 having left hand threads 40 thereon. The frame and rollers 30 may be of any suitable form, depending upon the work to be formed, and are provided with internal left-hand threads 41 co-mating with threads 40 upon the stub shaft 39, whereby their 100

105

110

tation and contact with the work will not loosen them from the shaft 39. The journal member 32 comprises a sleeve 42 into which telescopes a sliding shaft 43 carrying a transverse journal box 44 extending in hub-like formation as at 45, and depending from which hub-like formation is a rod 46. Carried integral with the sleeve 42 is a boss 47 providing a sliding bearing for the rod 46, and beneath the boss 47, upon the rod 46, is carried a helical spring 48 which yieldingly holds a bearing element 44 downwardly relative to the sleeve 42. Affixed to the sleeve 42 is a yoke 49 by bolt members 50 passing through the terminals of the yoke 49 and into bosses 50' carried by the sleeve 42. Passing through the middle portion of the yoke member 49 is an adjusting screw 51 turned by a crank 51' which adjusting screw 20 seats in a boss 52 above the journal portion 44 so that, upon the turning of the crank 51, a vertical adjustment may be had in one way against the yielding of the spring 48. Further angular adjustment may be obtained by mounting the journal member 32 to rotate about a pivot 32' on a standard 32" secured to table 2, and by providing said member with a clamping screw 53 extending through arcuate slot 54 in said standard 32" 30 to clamp the journal 32 to said standard 32" in any desired angular position.

Carried by the shaft 31 may also be cutting disks such as 55 which may likewise cooperate with elements carried by the shaft 35 for any desired forming or cutting operation. Carried by the table 2 is also a work support roller 56.

In operation, when power is applied to the shaft 4 by the co-meshing of the chain of 40 gears, the shaft 10 is also driven by like power so that the turret 12 rotates simultaneously with the forming wheel 30 in the desired or predetermined speed ratio and the work carried by the turret 12 is suitably 45 formed by the forming wheel 30. It is obvious that any of these elements may be quickly slid from the table 2 and other suitable elements placed in position.

I claim—

50 1. In combination in a sheet metal forming device, a bed, a turret for carrying the work to be formed, a forming wheel, a shaft carrying the forming wheel, mechanism for vertically and angularly adjusting the shaft,

and means for locking said mechanism and 55 shaft in adjusted position.

2. In combination in a sheet metal forming device, a turret for carrying the work to be formed, a forming wheel, a shaft carrying the forming wheel, means for vertically and angularly adjusting the shaft relative to the turret, and means for simultaneously rotating said turret and shaft.

3. An adjustable journal member for a sheet metal forming roll shaft, including a member adapted to journal the shaft and having a cylindrical part depending therefrom, a sleeve in which said part is slidably mounted, a yoke carried by the sleeve and extending above said member, an adjusting 65 screw threaded into said yoke and engaging said member to move it relative to said sleeve, and yielding means between said sleeve and member to maintain said member in contact against said screw. 70

4. A sheet metal forming machine, comprising a bed, a standard fixed to said bed, a turret slideable on said bed toward and from said standard, a bearing, means for vertically and angularly adjusting said bearing on said standard, a shaft rotatable in said bearing, a forming wheel on said shaft, and means for rotating said shaft at all positions of adjustment of the said bearing. 75

5. A sheet metal forming machine comprising a bed, a standard fixed to said bed, a turret slideable on said bed toward and from said standard, a shaft rotatable on said standard, and having a forming wheel at one end thereof, means for vertically and angularly adjusting said shaft on said standard, means for clamping said shaft in angularly adjusted position on said standard, and means for rotating said shaft in all positions of vertical and angular adjustment thereof. 80

6. In a shaft adjusting mechanism for a sheet metal forming device, in combination, a member adapted to journal the shaft and provided with a depending cylindrical member, a sleeve in which said cylindrical member is mounted, a boss carried by the sleeve, a rod depending from the journal member and slideable in the boss and having a nut at the free end thereof and a spring between said boss and nut. 100

In testimony whereof I affix my signature.

CHARLES JOHANSON.
